D7-301

EX

OR D 8,881

UNITED STATES PATENT OFFICE.

FRANK H. SHEPHERD, OF BOSTON, ASSIGNOR TO JAMES W. TUFTS, OF MEDFORD, MASSACHUSETTS.

DESIGN FOR THE CASING OF A SODA-WATER APPARATUS.

Specification forming part of Design No. 8,881, dated December 28, 1875; application filed December 2, 1875.
[Term of Patent 14 years.]

CASE G.

To all whom it may concern:

Be it known that I, FRANK H. SHEPHERD, of Boston, in the county of Suffolk and State of Massachusetts, have invented and produced a new and original Design for the Casing of a Soda-Water Apparatus, of which the following is a full, clear, and exact description, reference being had to the accompanying photograph making part of this specification.

In the photograph, A represents the base or lower portion of the casing of a soda-water apparatus, which is of rectangular form. B is the body or main portion of the casing, composed of a lower portion, c, a central portion, d, and an upper portion, e. Each of the four sides of the portion c slopes or inclines inward and upward from the base A to the cornice f, and is provided with an ornamental projection, g, which rests on the base A. The central portion d is of rectangular form, while the upper portion e is formed in the shape of a dome, which is provided at its top with a cap,

h, from the four corners of which rise the pillars i, which support the dome k, forming a belvedere, C, a beautiful and unique design being thus produced.

At each corner of the base A is a standard, m, for a gas-burner; but these standards may be dispensed with, if desired.

What I claim as my invention, and desire to secure by Letters Patent, is—

1. The design for the casing of a soda-water apparatus, substantially as herein shown and described.
2. The belvedere C, applied to the casing of a soda-water apparatus, substantially as shown and described.

Witness my hand this 18th day of November, A. D. 1875.

FRANK H. SHEPHERD.

In presence of—

P. E. TESCHEMACHER,
W. J. CAMBRIDGE.
